US00D519918S

(12) **United States Design Patent** (10) **Patent No.:** **US D519,918 S**
Wilson et al. (45) **Date of Patent:** **** May 2, 2006**

(54) **PORTABLE BATTERY**

(75) Inventors: **Christopher A. Wilson**, Fishers, IN (US); **Benjamin B. Rondot**, Noblesville, IN (US); **Jay C. Smith**, Grapevine, TX (US)

(73) Assignee: **Technuity, Inc.**, Indianapolis, IN (US)

(**) Term: **14 Years**

(21) Appl. No.: **29/210,174**

(22) Filed: **Jul. 28, 2004**

(51) **LOC (8) Cl. 13-02**

(52) **U.S. Cl. D13/103**

(58) **Field of Classification Search** D13/102-106, D13/110, 118-119, 137.4, 184; 429/96-100, 429/121, 163, 176; D8/358

See application file for complete search history.
